UNITED STATES PATENT OFFICE.

FRANK CHRISTOPHER SCHWEND AND JOSEPH BENTON WILSON, OF MONTGOMERY, ALABAMA.

MOSQUITO-BAR FRAME.

SPECIFICATION forming part of Letters Patent No. 439,256, dated October 28, 1890.

Application filed April 2, 1890. Serial No. 346,332. (No model.)

To all whom it may concern:

Be it known that we, FRANK CHRISTOPHER SCHWEND and JOSEPH BENTON WILSON, citizens of the United States, residing at Montgomery, in the county of Montgomery and State of Alabama, have invented certain new and useful Improvements in Mosquito-Bar Frames; and we do declare the following to be a full, clear, and exact description of the invention, such as will enable others skilled in the art to which it appertains to make and use the same, reference being had to the accompanying drawings, and to the letters of reference marked thereon, which form a part of this specification.

Our invention relates to supports or frames for canopies or screens for protecting persons from flying insects.

It consists in certain details of construction, as hereinafter set forth, and particularly pointed out in the claims.

Figure 1 represents an improved frame applied to a bedstead for supporting a mosquito-bar, one of the cross-pieces being broken away. Fig. 2 is a view, on an enlarged scale, showing how the parts fit together.

The frame comprises two uprights A, which are adapted to be secured to the head-board or post or foot-board or post of the bed B, 30 preferably by means of screws C. We prefer to place them adjacent to the posts b, in order to give the greatest spread to the mosquito-bar.

To the top of each upright is hinged an arm D, having its rear end arranged to project somewhat beyond the back of the upright, as shown. In the front of the upright is cut a transverse notch a, and across the bottom of the arm D is a similar notch d. A brace 40 E, consisting of a bar having its ends shaped to enter the notches a and d by sliding into them laterally supports the arm D when it has been raised to a horizontal position.

Fastened to one edge of each arm and at each end thereof is a tongue F, composed of a strip of wrought-iron. The tongue projects beyond the end of the arm and its outer end f is turned at right angles, forming a hook-shaped rest for the cross-pieces G, which are 50 made long enough to fit the widest bed. They are adapted to engage with the tongues F by means of transverse saw-cuts g, extending partly through them from below. The saw-cut slips down over the tongue, bringing the

cross-piece between the end of the arm and 55 the hook f, the space being made of substantially the same width as the cross-pieces, so that they are firmly held and cannot swing about. By making the space between the saw-cuts at the two ends of each cross-piece the 6c same as the width between the tongues on the rear ends of the arms after the uprights have been attached to the bed the frame formed by the arms and cross-pieces is sure to be rectangular. The frame can be applied to 65 beds of different widths simply by making additional saw-cuts in the cross-pieces at suitable distances apart. When the cross-pieces are detached and the braces slipped out, the arms can be folded down against the 7c uprights, and the frame can then be packed for transportation or storage in a very small compass.

The frame is easily made, requiring no mortising. It is exceedingly cheap, and can 75 be fitted by the purchaser to any width of bed.

Having thus described our invention, what we claim and desire to secure by Letters Patent, is—

1. The combination, with the uprights, of 80 the arms extending therefrom, having each a tongue composed of a strip of metal and a cross-piece having transverse saw-cuts to fit over the tongues, substantially as described.

2. The combination, with the uprights, of 85 the arms extending therefrom, having at each end a tongue F, provided with a right-angled hook f, and cross-pieces G, having saw-cuts g, adapted to fit over the tongues and to lie between the ends of the arms and the hooks f, 90 substantially as described.

3. An improved mosquito-bar frame consisting of the uprights A, having the notches a, the arms D, hinged to the uprights and having the notches d, the braces E entering 95 said notches, the tongues F, projecting from the ends of the arms and having hooks f, and the cross-pieces G, adapted to receive saw-cuts g at any point, whereby the frame is capable of application to beds of different 100 widths, substantially as described.

In testimony whereof we affix our signatures in presence of two witnesses.

FRANK CHRISTOPHER SCHWEND.
JOSEPH BENTON WILSON.
